(57) **CLAIM**

The ornamental design for display device, as shown and described.

DESCRIPTION

FIG. 1 is a perspective view of a display device according to the present design with the screen expanded in an unfolded state;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof;

FIG. 8 is a perspective view of the display device when the display device is in an unfolded state;

FIG. 9 is a front view thereof;

FIG. 10 is a rear view thereof;

FIG. 11 is a left side view thereof;

FIG. 12 is a right side view thereof;

FIG. 13 is a top view thereof; and

FIG. 14 is a bottom view thereof;

FIG. 15 is a perspective view of the display device when the display device is in a folded state;

FIG. 16 is a front view thereof;

FIG. 17 is a rear view thereof;

FIG. 18 is a left side view thereof;

FIG. 19 is a right side view thereof;

FIG. 20 is a top view thereof; and

FIG. 21 is a bottom view thereof.

The broken lines indicate unclaimed portions of the article that form no part of the claimed design.

1 Claim, 15 Drawing Sheets
